WINDOW CLEANER

Filed July 22, 1927

UNITED STATES PATENT OFFICE

CHARLES J. THATCHER, OF NEW YORK, N. Y.

WINDOW CLEANER

Application filed July 22, 1927. Serial No. 207,630.

The invention relates to magnetically controlled window-cleaner apparatus, more especially of the electro-magnetic type, embodying a manually-movable, magnet member and a follower, the two being adapted to operate over opposite faces of a window, or other glass or similar surfaces, and at least one of said members carrying a cleaning element.

10 In an apparatus of this character, the follower member automatically follows the movement of the manually operable member, which is controlled preferably from the inner side of the window.

15 The present invention has for its object to provide a magnetic cleaning device sufficiently powerful and frictionless to dispense with the use of any special supporting means for the follower, and, if electromagnetic, so 20 constructed and arranged, furthermore, that it will not become overheated by the current. A further object of the invention resides in a novel form of cleaning element which may be associated therewith, and which will not only 25 effect a cleaning by one operation if desired, but will also enhance the cooling effect so that the magnetizable member will remain sufficiently cool during the operation of cleaning windows.

30 To this end, the invention comprises a novel construction not only of the magnetized member but also of the follower member and its cleaning pad, whereby the friction is reduced to the minimum necessary for useful operation. In this device, also, the electromagnet member may be thermally connected to a 35 cleaning element so as to afford a relatively large and cooled radiating surface to assist in maintaining the said magnetized member 40 at a not objectionably high temperature.

The nature of the invention, however, will best be understood when described in connection with the accompanying drawings, in which:

45 Fig. 1 is an end view, in part section, of the novel window cleaner shown in near approach to a pane of glass to be cleaned and with the magnetizing current off, the magnet and follower not being in contact with the 50 glass as in actual operation.

Fig. 2 is a front view, partly in section, of the elements indicated in Fig. 1.

Referring to the drawings, 10 represents a section of glass, such as a window pane, which it is desired to clean by means of the 55 novel cleaner hereinafter more fully set forth, said cleaner comprising a magnet to be used preferably upon the inner side of the glass 10 and a further member of material adapted to be attracted magnetically and located preferably on the outer side of the window—both being preferably connected by some suitable means as a cable or cord 11 in order to prevent the follower member from dropping to the ground accidentally or when the latter 60 is not magnetized. The cord 11 may also, of course, be attached to a hook (not shown) in or near the window frame, if desired.

The magnetic member may be a permanent magnet or an electromagnet constructed for 70 use with either direct or alternating current, and preferably the latter as in the embodiment herein described. The said member, to this end, comprises a pair of magnetizing coils 15 which surround laminated cores connected across the top by the laminated bar 16 which may also serve as a handle. About the latter, however, is preferably placed a member 17 of suitable insulating material 75 such as bakelite or wood, the under face of which may be arranged to carry a contact member 18 whereby the power circuit to the coils 15 may be closed when the handle is grasped, power being supplied thereto through conductors 19 from a suitable source 80 (not shown).

To the said coils, or to their pole pieces 20 or to the follower pole pieces 21, or to all, is adapted to be secured, so as to promote thermal conduction, shallow supports or pans 90 22 and 23 of metal, for example, aluminum, and in which pans cleaning material is to be held. For securing the said pan to the magnet or follower member, as well as to accommodate the respective pole pieces 20 or 21 which project therethrough, the bottom of the pan may be pierced at two points opposite the said pole pieces to provide corresponding openings for the insertion of said pieces; and ears or tabs 24 and 25 may be 100

blanked out therefrom and turned outwardly to afford securing walls upon opposite sides of the pole piece, being rigidly attached thereto as by means of securing screws 26 and 27. Furthermore, a longitudinal slit 28 and 29 may be provided in the bottom of the pan 22 and 23 between the pole pieces 20 or 21 to eliminate possible eddy currents in the pan when alternating current is used.

10 As stated, the said pan is designed to retain a cleaning material which may be in the nature of a pad 30 such as a pelt of lambs wool, felt, or, preferably, rubber sponge which has very little friction on glass when 15 wet, particularly with water containing even a trace of soap. This pad is mounted in the pan to project a substantial distance above its edge and is surrounded at its marginal portions with upstanding strips of rubber 31 to act as a squeegee to dry the glass by following the said pad, which latter is intended for use in moistened condition. The edge of said squeegee member is located preferably substantially flush with or slightly below the 25 pad surface; but the outer faces of the pole pieces 20 or 21 are located some distance below the said surface of the pad.

I have found that an appreciable friction 30 may develop between the metallic pole pieces and a glass of a window pane or the like over which the pad is caused to travel. To further reduce the friction, particularly in the follower member, there may be provided a plurality of buffer members 32 which are 35 secured to the bottom of the pan and project upwardly a slight distance, say a few thousandths of an inch, above the plane of the pole faces. These buffers are spaced, for example, upon opposite sides of the pole 40 pieces to prevent wobbling of the device, and may be faced with or composed of rubber or other material which, when wet, will exert a minimum friction. They are adjusted so as to contact with the glass prior to any possible 45 contact of the pole faces therewith; and if necessary to reduce the friction to a minimum, roller or ball-bearing casters may be substituted for the contacting end. The friction is thereby reduced to a minimum, being 50 substantially only that of the cleaning pad and the squeegee members surrounding the same, all of which, when wet, exert but very slight frictional resistance thereon. If such or equivalent means to reduce friction are not 55 used, the magnet required may be very heavy and cumbersome; and or when operating on very thin glass, the more powerful magnetic attraction thus exerted may unduly compress the cleaning pad material and cause excessive 60 friction.

Said squeegee members may be secured to the pan in any convenient manner; and, by way of example, the same are herein shown as positioned in separate channel members 65 for the four sides of the pan, being held by

squeezing the inner edge of the squeegee rubber in the channel members, which are then attached to the walls of the pan, as by riveting the same thereto. The pad itself may be variously shaped, but is herein indicated as 70 of rectangular form. Similarly, the follower member will have substantially the same shape and is also similarly constructed. Of course, no magnetizing coils are required for the follower; but a suitably shaped keeper 75 or armature member, laminated for alternating current, is provided, the leg members or pole pieces 21 thereof extending into the said pan and being held thereto similarly to the pole pieces 20, as by the tabs 25 of the 80 pan 23 and screws 27. Buffer members 34 may also be provided in connection with this pad to prevent contact of the pole pieces 21 with the outer face of the glass, the reduction of friction to a minimum being of more importance in the follower. The bar portion 35 of the follower, moreover, affords a convenient member for manipulating the pad, which may be used for cleaning independently of the magnetized member, if desired. 85

The cleaner hereinbefore described may be utilized without any support for the follower member other than the magnetic pull exerted thereon by the magnetized member which controls the movement of the said follower over the opposing surfaces of the glass to be cleaned; and if both members are provided with pads, as herein disclosed, both faces of the glass may simultaneously be cleaned as the magnetized member is manually moved over the said glass—one passage over the glass sufficing to both clean and dry both sides of the window. 95

In applying the novel cleaning apparatus to a lower window, the latter is first elevated somewhat to allow of bringing the follower, say, to one of the lower corners of the outer face, whereupon the magnetized member is brought into juxtaposition and raised to an upper corner, after the window 100 has been closed, and then swept across, back and forth at different heights until the final lower corner is reached, the squeegee portion following the cleaning pad in every movement to dry the cleansed portion. Thereupon, the window is opened, and the magnetized member is withdrawn as well as the follower, freed thereby; and the squeegee portion of the same is manually drawn over the corner to complete the drying. 111

In certain cases it is desirable to elevate the lower window and first place the magnet and the follower with their cleaning pads in juxtaposition near an upper corner, and thereupon sweep the cleaning device across 115 the upper margin of the window to clean the same, the window remaining partly elevated meanwhile. Thereupon the follower and magnet are removed from the upper portion and placed in a lower corner and the 120

cleaning operation previously described thereupon followed in such manner that the first sweep across the upper portion of the window will overlap the portion along the upper margin first cleaned. This procedure will obviate complete closure of the window until the cleaning operation has been completed.

In like manner, an upper pane may be cleaned by bringing it to the lower portion of the window frame and elevating the lower pane to the upper portion of the frame, preferably after the upper margin of the upper window has been first cleaned by a passage of the cleaning device. The upper pane may also be cleaned by lowering it somewhat and placing the magnet and follower in juxtaposition at an upper corner and then proceeding as before described.

It will be understood that other forms of magnets, such as direct current magnets or permanent magnets may be used instead of the laminated core, alternating current magnet specifically described herein; and that in the case of direct current magnets, the lamination of the core may be dispensed with; and, in the case of permanent magnets, the heat-reducing or cooling device becomes unnecessary. Electromagnets of the straight-bar type, that is, with a coil or coils placed on a straight bar and bare pole pieces extending into the cleaning pad, or other types may be used; and other changes may be made in the device without departing from the spirit of my invention.

Also, while the cleaning device has been shown as composed of a central pad 30 and a squeegee member 31, it will be understood that the cleaning and drying operations may be effected separately using these members alone.

I claim:

1. A magnetically controlled window cleaner, comprising a magnet and a cooperating follower adapted to operate over the opposite faces of the window, and a squeegee member carried by one of the cooperating magnetic members.

2. A magnetically controlled window cleaner, comprising a magnet and a cooperating follower adapted to operate over the opposite faces of the window, and a cleaning member comprising a pad and a squeegee member carried by one of the cooperating magnetic members.

3. A magnetically controlled window cleaner, comprising a magnet and a follower adapted to operate over the opposite faces of the window, a cleaning member carried by one of the said cooperating magnetic members comprising a metallic support, the cleaning member and the support being pierced to receive the poles of its magnetized member.

4. A magnetically controlled window clean-

er, comprising a magnet and a follower adapted to operate over the opposite faces of the window and one of which carries a cleaning member comprising a metallic support thermally connected with the magnetized member, a washing and cleaning pad thereon, channel members secured to the sides of said support, and strips of rubber held in the bottom of said channels and extending above the edges of the pan.

5. A magnetically controlled window cleaner, comprising a magnet and a follower adapted to operate over the opposite faces of the window, a cleaning member carried by the follower, and friction-reducing means associated with said cleaning member.

6. A magnetically controlled window cleaner, comprising an electromagnet and a follower adapted to operate over opposite faces of the window, a cleaning member carried by the follower and embodying a support, a pad held thereon adapted to be moistened and a squeegee member secured to the support along a margin of the pad, the bottom of the support being pierced to receive the pole pieces of the electromagnet, and buffer members having relatively frictionless contact surfaces and extending upwardly from the bottom of said support above the plane of the pole faces of the follower.

7. A magnetically controlled window cleaner, comprising an electromagnet and a follower adapted to operate over opposite faces of the window, a cleaning member carried by the follower and embodying a support, a pad held therein adapted to be moistened and a squeegee member secured to the support along a margin of the pad, the bottom of the support being pierced to receive the pole pieces of the electromagnet, and buffer members having relatively frictionless contact surfaces and extending upwardly from the bottom of said support above the plane of the pole faces of the follower and spaced upon opposite sides thereof.

8. A magnetically controlled window cleaner, comprising a magnet and a cooperating follower adapted to operate over opposite faces of a window, and a cleaning member comprising a rubber sponge pad.

9. A magnetically controlled window cleaner, comprising a magnet and a cooperating follower adapted to operate over opposite faces of a window, and a cleaning member comprising a rubber sponge pad, and a squeegee member along a margin thereof.

10. A magnetically controlled window cleaner, comprising a magnet and a cooperating follower adapted to operate over opposite faces of a window, and a cleaning member provided with buffer members to adjust the distance of the pole pieces of the follower from the window.

11. A cleaning member, comprising a support, a pad held thereon and adapted to be

moistened, and buffer members having relatively frictionless contact surfaces and extending upwardly from the bottom of said support to a plane below the face of the pad.

5 12. In a magnetically controlled window cleaner, the combination of a magnet having pole pieces and a separating yoke adapted to be used as a handle, and a cleaning follower with similarly spaced pole pieces and adapted to operate over the opposite face of a window.

10 13. A magnetically controlled window cleaner, comprising a magnet and a follower adapted to operate over the opposite faces of a window and having pole pieces, a cleaning member penetrated by the said pole pieces of the follower, and means to prevent contact of said pole pieces with the surface of the window.

15 20 In testimony whereof I affix my signature.
CHARLES J. THATCHER.
